[57] **ABSTRACT**

There is provided an apparatus and process for providing the desired density and consistency characteristics in rolls of wet material — e.g., newspaper rolls, which are used in subsequent operations such as newspaper printing and where the properties of the roll are to be matched to those required during the subsequent operation.

SHEET 2 OF 2

**PROCESS AND APPARATUS FOR WINDING
SHEET MATERIAL**

This invention relates to an apparatus and process. More particularly, one aspect of this invention relates to an improvement in the formation of rolls of sheet material, as for example, during the rewinding of rolls of sheet paper.

In the manufacture of various types of sheet material, such as rolls of newsprint paper, the sheet paper is formed by conventional techniques, which, briefly summarized, include the steps of forming a paper web from a slurry of paper-forming material (such as cellulose fibers), drying the web to form a dried sheet of paper and subsequently winding the dried sheet paper onto rolls.

The rolls of sheet paper when, for example, employed in newsprint operations, must be manufactured to high tolerance requirements. For example, newsprint operations involve high speed processes where paper must be unwound from rolls at high speeds. Unless the quality of the paper roll is of a certain standard, the roll of sheet paper will not "run" properly during printing operations. Moreover, as is known to those skilled in the art, due to the different nature of machines involved in newsprint operations, different requirements for the rolls of paper have to be provided for different types of machines in order for the roll of paper to perform properly.

Briefly summarized, the rolls of sheet paper must be free from undulations and have a consistency such that the paper is capable of being unwound from the roll at high speeds without breaking; and moreover, the sheet paper rolls must not be wound so tightly as to be liable to split during transporting of the rolls. Additionally, other requirements for sheet paper rolls are that they must not have any flat spots — i.e., where the roll is out of symmetry (it must be substantially perfectly cylindrical). Failure of a wound roll of sheet paper to meet these requirements results in unacceptable rolls and hence may lead to frequent shut down of equipment during subsequent processing operations — i.e., newsprint manufacture. Additionally, the rolls tend to split if wound too tightly, thus rendering the rolls useless.

The roll of sheet paper as it is produced from a paper-making operation does not meet the above requirements and accordingly it is conventional practice in the art to rewind the roll to produce a tightly wound roll which has "acceptable" properties of paper tension and consistency. To this end, conventionally the rolls of paper from a paper-making operation (termed the "parent" roll) are rewound by passing the paper over a supporting platform, subsequently passing the paper sheet beneath a first rotatable drum (known in the art as a "rear" drum) whereafter it is wound onto a core which is driven by a further spaced-apart drum (known in the art as a "front" drum) mounted in operative relationship to the core onto which the paper is being rewound. Both the front and rear drums are conventionally driven at a constant speed by a common drive means, and both in turn frictionally drive the rewind paper core.

Rewinding operations are normally high speed processes, involving speeds of up to 7,000 feet per minute or more. To this end, the parent roll to be rewound is mounted on a suitable supporting apparatus which includes a reel bar or shaft mounting the paper roll, the

reel bar being provided with a braking apparatus tied in to the drive rotating the roll onto which the paper is being rewound. The brake serves to frictionally engage the reel bar of the parent roll to arrest its rotation when and if desired depending on the speed of operation of the finished roll, in order to prevent paper being fed from the parent roll when rotation of the finished roll is halted. In such operations the front drum is the critical component in that the torque exerted by the front drum on the rewind roll is a major factor in determining the density of the finished roll throughout the rewinding process. At present, conventional practices do not include torque control on the rewind roll through either the front or rear drums but rather, the conventional practice uses a brake on the parent roll to control the tension on the sheet or web of paper and provide some degree of control in the paper tension and consistency of the finished roll. This, however, provides finished rolls of a very wide latitude and inconsistency of density and it has been found that due to the lack of control, a percentage of rolls split during transportation or do not have the desired properties for subsequent processing; nor for that matter, is there any uniformity between rolls so as to have constant unwind characteristics or permit the rolls to be universally adapted for use on each and every type of equipment employed in e.g., newspaper printing. The importance of this will be evident when considering the characteristics required for a roll unwinding at, e.g., 5,000 feet for e.g., newspaper presses. Typically, finished paper rolls according to conventional practices may have a paper tension at the core of 3.5 pounds per linear inch decreasing outwardly from the center of the roll to approximately 0.5 pounds per linear inch. In general, for perfect unwinding conditions at the presses, the tension of each sheet layer of the unwind roll (i.e., the stored tension of each layer) should be approximately the same as the tension exerted on the sheet material as it is pulled from the unwind roll. As it is known to those skilled in this art, lower paper tensions are encountered during initial unwinding of the roll, and increase to higher values at the center of the roll due to greater friction by, e.g., the core rotating far faster towards the end of the unwinding operation, and with additional friction being created by the friction brake normally employed. Under conventional conditions, as previously mentioned, it is substantially impossible to attain a finished roll which matches the characteristics required during the complete unwinding operation and the progression of the tension from the above typical values — i.e., from 3.5 to 0.5 pounds, is not suitable nor programmed for any and all operations.

The above limitations of the prior art are further brought out by the fact that the paper producers typically manufacture newsprint paper which has tensile strength of approximately 8 pounds per linear inch. This relatively high degree of tensile strength is required for, amongst other reasons, the high degree of stress to which the paper is subjected during unwinding at the newsprint presses. Thus, the tensile strength of the paper must be such that it is capable of withstanding the flutter and other vibrations as it is being unwound from the finished roll, which vibrations and flutter occur as a result of the finished roll not possessing the required characteristics to enable it to be unwound smoothly at the high speeds encountered during winding. Thus, if it were possible to provide a finished roll

which had the necessary degree of paper tension and consistency to unwind, at high speeds in a smooth and continuous manner without flutter or other vibrations, the degree of tensile strength otherwise required for the paper in the finished roll could be reduced substantially without any sacrifice in the properties of the paper.

With this invention, applicant has developed according to one aspect a method and apparatus which overcomes the above deficiencies while at the same time providing a given desired tension and consistency for rolls of sheet material according to preselected factors, which method and apparatus are particularly adapted to the rewinding operation of newsprint or similar rolls, although not limited thereto.

In accordance with one embodiment of the present invention, there is provided an apparatus suitable for forming a web of sheet material into a roll of said sheet material having desired density and consistency characteristics wherein said apparatus includes means for winding the sheet material on a rotatable core, means for rotating said rotatable core, said last-mentioned means comprising first and second spaced-apart rotatable driven means each adapted to form a nip point with sheet material on said rotatable core and to rotate said rotatable core through frictional engagement with said sheet material wound on said rotatable core, and separate drive means for each of said driven means, the improvement comprising variable torque control means connected in operative relationship to one and only one of said driven means mounted in the downstream direction of movement of said sheet material, for rotating said rotatable core.

According to a further preferred form of the above embodiment, there is also provided a paper elasticity sensor, said elasticity sensor comprising a pair of spaced-apart rotatable rollers between which a web of paper is adapted to pass as it is being rewound from said first roll of paper into a rewind roll, said rollers comprising an upstream roller and a downstream roller in the feed direction of the web of paper, the upstream roller being provided with braking means adapted to provide a frictional brake constant, said rollers being rotatable by the movement of the web of paper, and means for measuring a difference in the relative rotation between said pair of rollers to provide an electrical output signal proportional to the relative speed of said rollers. According to this embodiment, the paper elasticity sensor preferably operates in conjunction with suitable computer means adapted to receive the electrical signal generated by said above-mentioned means, and to provide an electrical output signal to the torque control means connected to the drive means of said means for rotating said rewind paper roll.

According to the present invention, the rewind paper roll is conventionally mounted by means of a core shaft between a pair of driven rotatable rollers or drums termed "front" and "rear" drums. The driven rear drum is in frictional engagement with the rewind paper roll, forming a first nip point in contact therewith, between which the sheet passes. In practice, the rewind paper roll is conventionally mounted on a core shaft and may or may not be mounted by suitable means for displacement of the roll during the rewinding process. The front drum, on the downstream side in the direction of feed of the web to the rewind roll, is normally a drum which frictionally drives the paper roll as it is being rewound. To this end, the drum is normally in

frictional contact with the paper roll thereby forming a second nip point. The front and rear drums may be any suitable conventional type, well known to those skilled in the art, typically being around 24 inches in diameter. Any suitable motor means may be provided for separately driving the front and rear drums, such as a D.C. electric motor, again well known to those skilled in the art.

The torque control means connected to the drive means for the front drum may be of any suitable type, such torque control means being well known to those skilled in the electrical art. To this end, the torque control means is preferably of the manually or automatically adjustable type, capable of being set to provide a selected desired degree of torque control. In this manner, the front drum torque control will thereby provide a micro-control necessary to obtain the exact required roll density and other characteristics in the finished roll, at any and all points in that roll. In the embodiment of the present invention where the torque control means is adapted to be manually operated, the manual operation may include the use of a fixed cam structure mounted in operative relationship to the torque control means for the front drum whereby the cam means programs the increase or decrease in the torque control exerted by the drive means for the front drum, which will thereby increase or decrease the tension placed on the sheet material as it is being wound to form a finished roll. In the embodiment of the invention where the torque control means is operated in conjunction with the elasticity sensor, the torque control means is preferably of the automatic type responding to a predetermined signal from the sensing device to increase or decrease the torque required to provide finished rolls having the desired degree of tension and consistency, as hereinafter described.

The spaced-apart rolls of the paper elasticity sensor may each be of similar construction, with the exception that the upstream roller is provided with suitable braking means as hereinafter described. More particularly, each roller is freely mounted by suitable means — e.g., roller bearings and positioned by suitable frame members in the desired line of travel of the web. To this end, the downstream roller may be displaceably mounted by, for example, hydraulic or pneumatic means, to permit threading of a paper web between the rollers during start-up procedures for rewinding. Typically, each roller may be made of, for example, fiberglass, or various types of metals e.g., aluminum and magnesium and is preferably of a relatively light weight. To this end, the weight of the rollers may be reduced by using hollow cylindrical rollers as opposed to solid rollers.

The diameter of the respective rollers may vary considerably and need not be the same. Typically, in the high speed operations encountered during rewinding procedures, diameters of from 10 to 14 inches have been found to be suitable; with larger diameters being more suitable for higher speeds and smaller diameters for slower speeds.

The width of the rollers should be at least equal to the width of the web being rewound, and preferably is several inches greater, in order to provide a full width support for the web. Typically, widths for such rollers for newsprint rewinding operations vary from 127 to 369 inches, although larger or smaller diameters of course will be employed where and as necessary.

Should different diameters of the rollers be employed, suitable compensation will have to be provided in the output signals generated by the rollers so as to correlate the signals to a constant factor.

Any suitable brake means may be provided for creating a desired degree of braking action on the upstream roller to effect a differential rotation between the upstream and downstream roller and hence provide a different rotational speed to the tachometer means as hereinafter described. Typical of the brake means which may be employed are hydraulic or pneumatic brake means. Most desirably, the brake is connected in a closed loop to a sensor at one end, and at the other end to a reference voltage.

As described hereinbefore, the rotatable rollers operate in conjunction with suitable means for generating an electrical signal proportional to the respective speeds of the rollers. To this end, such means may include, for example, fluid amplifiers, tachometer generators or similar mechanical-electrical equivalents, tachometer generators preferred because of their relative simplicity and economical attributes. To this end, the tachometer generator provides a proportional signal to the computer means. The computer means may be any suitable computer device, such as an analog computer, a digital computer or other equivalent components. To this end, the computer means may be provided with a predetermined programmed constant (K), and is adapted to receive the output signal from the tachometer generator to provide a controlling signal to the torque control means connected in operative relationship to the drive means for the front drum device.

Preferably, according to a desired embodiment of the present invention, the generator means receives and provides a continuous output signal to provide a constant monitoring. However, if desired, discontinuous readings could be utilized.

As will be seen from the above description, where the torque control means is employed in conjunction with the paper elasticity sensor, a finished roll can be obtained having the desired degree of tension together with a desired paper elasticity factor. The significance of the paper elasticity factor is well known to those skilled in the art, and will become evident from the following description hereinafter. Thus, with the present invention, the desired elasticity can be "built in," and in practice, maximum elasticity in the finished roll can be obtained using the above description embodiments.

The above described process and apparatus may also be slightly modified and utilized for improving the quality of sheet material as the latter is formed in a parent roll. In this respect, and conventionally, in the paper making art, sheet paper material as it is produced is passed between a plurality of generally vertically arranged rollers, known as "calendar" rollers, whereafter it is wound onto a reel bar to form the parent roll as described above.

Formation of the parent roll by conventional practices known to those skilled in this art, normally involves taking-off the sheet or web sheet from between the lowermost pair of calendar rollers, generally termed the "queen" and "king" rollers, passing the sheet over a driven drum rotating about a fixed axis and onto a reel bar in contact at a nip point with the reel drum, about which the sheet material is wound.

During formation of the parent roll, the tension exerted by the reel drum, (initially on the reel bar and subsequently on the sheet paper wound on the reel bar) at the point where the nip contact occurs with the reel drum, represents the sole means of controlling the tension of the sheet paper in the parent roll. It has been found by the applicant that this tension factor in the parent roll is not adequate for high quality parent rolls, inasmuch as the resulting parent rolls have a high degree of susceptibility to creasing of the sheet material in the roll due to the lack of uniform tension of the sheet material.

Additionally, since the firmness or hardness of the roll is not controlled, the amount of paper (in terms of its length) is not generally accurately known and therefore conventional practice is to make additional paper to ensure an adequate length in the parent roll for a subsequently rewound roll. In practice, the extra length added to the parent roll over and above what is needed for the finished roll, is then scrapped and put back into the paper-making operation. Still further, there is no control in the production of parent rolls which enables the qualities of the parent roll to be matched to the speed of a rewinding operation, as hereinbefore described.

It is highly desirable that the tension of the parent roll be substantially uniform; and to the extent that the prior art can provide a control, this is accomplished by increasing the torque control on the reel drum of the parent roll during its formation. However, increasing the torque control results in the loss of elasticity due to a much higher torque being required than is actually necessary. The loss of paper elasticity means that the paper roll should be used immediately, or otherwise the percentage of elasticity lost becomes so high that the paper roll becomes unusable. In practice, for the above reasons, it is conventional to exert only a very minor amount of torque force on the sheet material, by the reel drum at the nip point with the parent roll. Moreover, it will also be obvious that by exerting a torque force at the nip point, the pull on the web from the calendar rollers tends to stretch it, which is a reason why the elasticity factor is lost. In other words, the stress on the sheet material was to such an extent that as the sheet material is not of a type which readily recovers (as in the case of a rubber-like substance), the elasticity factor is not recovered to any extent (to some extent the elasticity recovers in the parent roll).

Thus, by prior art procedures, it is theoretically possible to obtain a firm or hard roll by increasing the tension on the paper at the nip point formed by the reel drum and the parent roll, but this is accomplished at the expense of elasticity. For this reason, prior art procedures have employed only a very minor amount of torque force as exerted by the reel drum.

In accordance with this development, the above disadvantages are overcome by the hereinafter-described process. Briefly summarized, in accordance with one aspect, in a process for forming parent rolls of sheet material wherein the sheet material is passed over a first rotatable drum and engaged at a first nip point by said drum and a reel bar or partially formed parent roll, the improvement is provided wherein the tension of the sheet material is controlled in the parent roll by causing a torque force to be exerted on said reel drum or partially finished parent roll, at a point removed from said first nip point whereby the tension of said sheet mate-

rial in said parent roll is controlled between said first nip point and said point at which said torque force is applied to said sheet material.

In accordance with this further embodiment, in an apparatus for forming a parent roll of sheet material from a supply of sheet material wherein the apparatus includes a separately driven rotatable drum over or under which the sheet material is adapted to pass, and which apparatus further includes a rotatable rear roller mounted in operative relationship to the driven drum whereby a nip point is formed between which the sheet material is adapted to pass, the improvements comprising a second separately driven rotatable drum mounted in operative relationship to said wheel bar whereby said second drum provides a second nip point with said reel bar between which said sheet material is adapted to pass after passing through said first nip point, and means for rotating said second drum and for causing said second drum to engage said reel bar with a desired amount of torque force at said second nip point.

With the above-described apparatus and process, applicant has now found it possible to increase the tension on the paper at the nip point but without loss of elasticity. Thus, by applying a torque force at the second nip point, the tension between the two nip points is maintained after the sheet material is released from engagement with the second nip point, by friction between the respective layers of the sheet material forming the parent roll. Thus, the large area of friction between the first and second nip points holds the sheet material tensioned to what it was prior to release from the second nip point, thereby obtaining a hard or firm roll with substantially little loss in paper elasticity as compared to prior art procedures. The loss of elasticity by the process and apparatus above described may, for example, be in the order of from about 2 percent to about 3 percent, compared to up to 50 percent to about 70 percent by prior art procedures if and when employed, depending on the atmospheric conditions prevailing at the time of manufacture of the parent roll.

More particularly, in the apparatus and process of the present invention, the provision of a second nip point utilizing a desired torque force, results in the formation of parent rolls of sheet material having greatly improved properties — for example, a substantially uniform tension with substantially crease-free paper; and with the added advantage that due to the uniformity of the roll, the length of the sheet material can be more accurately gauged as compared to prior art parent rolls produced by conventional processes. Thus, by more accurately gauging the length of sheet material in the parent roll, the waste factor normally associated with prior art parent rolls can be decreased, which in turn eliminates the necessity of providing extra lengths of paper in the paper roll to ensure that the rewind roll has sufficient material.

In carrying out the above process and in using the apparatus, it is conventional for the reel drum and reel bar to contact each other at an angle of anywhere from about 30° to 50°, typically around 35° from the vertical axis of the reel drum, to form the first nip contact point. In this respect, the reel drum is conventionally driven by suitable means known to those skilled in the art; typically the drum serves to provide a paper feed rate of between about 1,500 to about 2,000 feet per minute. In practice, the reel drum is mounted for rotation about a fixed axis, supported by any suitable means.

The sheet material, as it is fed to the first nip point is conventionally provided from the calendar rollers of a paper-making operation; it suffices to say that those skilled in the art will understand the conventional procedure of feeding sheet material from the calendar rollers to the reel drum.

In conventional techniques, the sheet paper after passing over the reel drum is wound onto a reel bar as explained hereinbefore. Initially, therefore, it is the surface of the reel bar itself which forms the first nip point with the reel drum; thereafter, the sheet material is wound around the reel bar, the surface layer of the wound parent roll forms the nip point. Thus, as used in this specification in reference to the nip point, it is to be understood that reference to the reel bar will include the situation where the sheet material on the reel bar likewise forms the nip point.

In accordance with this invention, the second nip point is preferably formed at a point approximately equal to one-half the circumference of the sheet paper travel on the reel bar, or in other words, the second nip point is preferably formed on an axis substantially the same as the axis intersecting the centers of the reel drum and reel bar, to provide a substantial sheet area, in the direction of travel of the sheet material on the reel bar, between the first and second nip points. However, if desired, the second nip point may be spaced closer to or further from the preferred position of the second nip point and still retain the advantages of the present invention.

The second nip point may be formed by employing a rotatable roller or drum rotating about a fixed axis and driven by a suitable means such as an electric motor. The roller or drum may be mounted by any suitable means, such as by a central axis, and will be spring-loaded for movement about a fixed path to compensate for the increased thickness of the parent roll as it is being formed. Thus, for example, the drum may be spring-loaded to maintain it in engagement with the reel bar.

Having thus generally described the invention, reference will now be made to the accompanying drawings illustrating preferred embodiments and in which

FIG. 1 is a schematic side elevational diagram of a preferred embodiment of the present invention;

FIG. 2 is a schematic diagram of the apparatus of FIG. 1 showing the connection between the sensing device, means for generating an electrical signal, a computer and the torque mechanism;

FIG. 3 is a schematic view of the sensing device shown in FIG. 1; and

FIG. 4 is a perspective schematic view of an apparatus according to a further modification of the present invention.

Referring initially to FIGS. 1 to 3, there is schematically illustrated a device according to the present invention for rewinding sheet paper rolls, in conjunction with a typical rewinding operation involving slitting of the paper.

More particularly, a roll of sheet paper 22 as would be obtained from, for example, a paper-making process, is mounted by means of a reel bar 20 and suspended or positioned by suitable supporting means (not shown). The roll 22 as it comes from a paper-making operation is, relatively speaking, loosely wound and must be further processed to slit the sheet material to a desired width. Conventionally, the core shaft (reel

bar) 20 is provided with a suitable brake mechanism to control the feed rate.

As illustrated in FIG. 1, the roll 22 is rewound into a further roll indicated by reference numeral 30 mounted on a core shaft 32, the roll 30 after being processed having the desired degree of consistency and capable of withstanding unwinding at the high speeds encountered during subsequent processes, or processing. Operating in conjunction with the rewound roll 30 is a first separately driven rear rotatable drum 34 mounted on shaft 36 and a second separately driven rotatable front drum 38 mounted on a shaft 40. The front drum 38 is in frictional engagement with the paper roll 30 (thus forming a first nip point) and serves to rotate roll 30 for rewinding purposes. To this end, shafts 36 and 40 are each separately driven by a suitable motor means (not shown). Likewise, shaft 36 rotates drum 34 which is in engagement with roll 30, thus forming a second nip point. If desired, as is conventional practice in this art, supplementary means adapted to initially aid the rotation of the paper roll 30 may be provided in the form of a rider roller (not shown). To this end, the rider roller typically engages the paper roll 30 during the initial stages of formation of the roll 30.

In accordance with this invention, the power means driving the shaft 40 and the drum 38 are coupled in operative relationship to a torque control means 42 adapted to provide a microswitch in the power drive means for the shaft 40 to control the sheet density of the rewound paper roll 30. In this respect, control 42 thereby controls the torque force and provides an additional motor control during driving or rotation of the roll 30 to provide the improvements in the rewound paper roll according to the present invention. Thus, the present invention provides a control whereby applicant may obtain 100 times or better the accuracy may obtain in providing a desired degree of tension and other characteristics in a finished roll as compared to any prior art techniques.

From the above, it will be seen that by applying a torque force to the sheet material at the second nip point, the tension between the two nip points is maintained after the sheet material W is released from the second nip point by the friction between the respective layers of the web W on the roll 22.

Operating in conjunction with the above-described apparatus and according to one embodiment of this invention, there is provided a paper elasticity sensor. According to the embodiment illustrated, the elasticity sensor comprises a pair of rotatable rollers 50 and 52 mounted in a spaced-apart relationship between which a sheet of paper indicated by reference letter W is adapted to pass from the paper roll 22 as it is being fed to the rewind roll 30. Rollers 50 and 52 are journaled on shafts 54 and 56 respectively. Additionally, suitable braking means are connected to roller 50, such as a hydraulic or pneumatic brake means to provide a constant brake factor.

Operating in conjunction with the elasticity sensor device is a suitable tachometer generator indicated generally by reference numeral 58, connected electrically by leads 60 and 62 to rollers 50 and 52 respectively. Rotation of the rollers 50 and 52 feeds to the tachometer generator an electrical signal proportional to the respective speeds of the rollers 50 and 52. Operating in conjunction with the sensing device, is a computer means 64, receiving a signal via connection 66

from the tachometer generator 58. In turn, the computer 64 feeds an input signal to the torque control device 42 based on the elasticity constant of the paper which is being continuously monitored by the tachometer generator and the sensing device.

By employing the sensing device as described above, there will be provided in the finished roll, a maximum elasticity in combination with the other attributes hereinbefore described. Thus, due to the continuous sensing of the elasticity of the paper as it is being fed to the roll 22, a continuous measurement is provided (according to a preferred embodiment) which may be then translated into the finished roll as described above.

The apparatus of FIG. 1, as illustrated, may be used in conjunction with a conventional slitter table indicated generally by reference numeral 26 with slitters 28 slitting the paper to a desired width as it is being wound. Guide roller 24 may be mounted to position the web W as it is being fed from roll 22 to rewind roll 30.

Referring now to the embodiment as illustrated in FIG. 4, there is illustrated schematically a portion of the calendar set-up conventionally employed in paper-making operations as indicated by the plurality of vertically arranged rotating rollers 100, 102, 104 and 106 which, in practice, are journaled on rotatable shafts driven by suitable means. The lowermost pair of cooperating rollers 104 and 106 are known in the art as queen and king rollers respectively; a sheet of paper material being taken-off the king roller 106. The sheet of paper material, indicated by reference letter W, is conventionally fed about a reel drum 108 rotating about a fixed axis and conventionally mounted on a shaft 110. The web W passes in engagement with the surface of the reel drum 108, and is wound about a reel bar indicated by reference numeral 112. The reel bar 112 and reel drum 108 are mounted in juxtaposition with each other, and form a nip point indicated generally by reference numeral 114 between which the web W passes as it is being wound onto the reel bar 112. As such, nip point 114, according to conventional practice, forms the only control of the tension of the sheet paper wound onto the reel bar and forming a roll 116 thereof. As explained hereinbefore, this tension control according to prior art procedures is inadequate to provide the desired properties in a parent roll 116.

In accordance with this invention, there is provided a further driven roller 120 mounted on a shaft 122 and rotating about a fixed axis. Roller 120 forms with the reel bar and a second nip point 124, nip point 124 being located according to a preferred embodiment at a point approximately equal to one-half the circumference of the distance of travel of the web W about the reel bar 112.

Although not illustrated in the schematic drawing, it will be understood that reel bar 112 and roller 120 are mounted by suitable means as, for example, a mounting bracket connected to the shafts of the respective bar 112 and roller or drum 120, which mounting shafts are adapted for movement about a fixed path to compensate for the increase in thickness of the reel bar as the paper is wound thereabout. Likewise, the mounting arms will be spring-loaded to provide a desired degree of tension between the reel bar 112 and reel drum 108 at the nip point 114; likewise, in the case of roller or drum 120 and reel bar 116, the latter roller or drum 120 is preferably provided with adjustable spring-

loading means to vary the force at the nip point 124.

As will be seen from the above description, the tension applied to the web W as it is being wound about the reel bar 112 to provide a parent roll, may be directly controlled by exerting a desired degree of force at the nip point 124, whereby the parent roll may be wound to have a desired degree of tension. In a typical process, the tension exerted on the web W between the nip points 114 and 124 will vary between about one-fourth to one-half pound per linear inch of the web, which has been found to produce parent rolls having improved properties for subsequent use, particularly, for rewinding operations as described hereinbefore. However, the amount of tension may vary to higher or lower forces depending on the characteristics desired in the parent roll.

From the above, it will be seen that there may be obtained parent rolls having a desired degree of elasticity combined with a desired firmness, in contrast to prior art procedures which were not capable of attaining a similar type of parent roll.

In the above described embodiments, and as illustrated in the drawings, reference has been made to sheet paper material for use in the process and apparatus of the present invention. It will be understood, however, that the present invention is not limited to the use of sheet paper material but may also advantageously be used with other sheet materials, such as sheet textiles, sheet plastic film, and various types of sheet materials.

It will be understood that variations from the above may be made without departing from the spirit and scope of the invention.

I claim:

1. In an apparatus suitable for forming a web of sheet material into a roll of said sheet material having desired density and consistency characteristics wherein said apparatus comprises in combination:

means for winding the sheet material on a rotatable core, means for rotating said rotatable core, said last-mentioned means comprising first and second spaced-apart rotatable driven means each adapted to form a nip point with sheet material on said rotatable core and to rotate said rotatable core through frictional engagement with said sheet material wound on said rotatable core;

separate drive means associated with each of said driven means; and variable torque control means connected in operative relationship to one and only one of said driven means mounted in the downstream direction of movement of said sheet material, for rotating said rotatable core.

2. An apparatus as defined in claim 1, wherein said apparatus includes means for providing a web of sheet material to be wound onto said rotatable core, said last-mentioned means comprising a supply of said sheet material mounted for movement about a fixed axis, elasticity sensor means for detecting the elasticity of said sheet material between said supply of sheet material and said rotatable core, said variable control means being responsive to said sensor means.

3. An apparatus as defined in claim 2, wherein said elasticity sensor means comprises a pair of spaced-

apart rotatable rollers rotating about a fixed axis, said rollers being displaced one from another in a horizontal plane, one of said rollers having braking means associated therewith adapted to provide a frictional brake constant, the other of said rollers being freely rotatable, and means for measuring a differential in the relative rotation between said rollers to provide an output signal proportional to the relative speed of said rollers.

4. The apparatus of claim 3, wherein said apparatus includes computer means adapted to receive said output signal, said computer means being adapted to provide an output signal to said torque control means.

5. In a method of winding sheet material into a roll thereof having desired properties of tension and consistency, wherein a source of sheet material is formed into a roll thereof the improvement comprising constantly controlling the tension of the sheet material as said roll is being formed by passing said sheet between a pair of spaced-apart nip points and exerting a variable torque force on the nip point in the downstream direction of movement of said sheet material compared to the torque force on the nip point in the upstream direction of the movement of the sheet material.

6. A method, as defined in claim 5, wherein during winding of said sheet material into a roll thereof, there is included the step of monitoring the elasticity of said material prior to said material being wound into a roll.

7. A method as defined in claim 6, including the step of passing said sheet material through a pair of spaced-apart rollers which rotate about a fixed axis, one of said rollers having braking means associated therewith and the other being freely rotatable to thereby obtain a differential in the relative rotation between said rollers and thus to provide an output signal proportional to the relative speed of said rollers to determine the elasticity of said sheet material.

8. A method as defined in claim 7, including feeding said output signal to a computer means.

9. A method as defined in claim 8, wherein there is provided an output signal from said computer means, said last-mentioned output signal governing means controlling said tension imparted to said sheet material as said roll is being formed.

10. In a method of winding sheet material into a roll thereof having desired properties of tension and consistency as defined in claim 5, wherein a source of sheet material is formed into a roll thereof, the improvement comprising controlling the tension of the sheet material as said roll is being rotated about a fixed axis, monitoring the elasticity of said material as said material is formed into said roll by passing said sheet material between a pair of spaced-apart rollers rotating about a fixed axis, one of said rollers having braking means associated therewith and other being freely rotatable thereby to obtain a differential in the relative rotation between said rollers whereby there is obtained an output signal relative to the elasticity of said material, feeding said output signal to a computer means and controlling said torque relative to the material being wound to form said roll with respect to the elasticity of said material as it is being wound in proportion to said output signal.
